UNITED STATES PATENT OFFICE.

JOHN S. HOBSON, OF CHICAGO, ILLINOIS, ASSIGNOR TO THE UNION SWITCH & SIGNAL COMPANY, OF SWISSVALE, PENNSYLVANIA, A CORPORATION OF PENNSYLVANIA.

LIGHT SIGNAL.

Application filed August 24, 1922. Serial No. 584,144.

My invention relates to light signals, and is particularly well adapted for signals of this type which are used in railway traffic controlling systems.

5 One feature of my invention is the provision of a backlight which is visible from a train after passing the signal, whereby the engineer or other persons on the train may be informed that the signal indicates "stop".

10 I will describe one form of signal embodying my invention, and will then point out the novel features thereof in claims.

In the accompanying drawings, Fig. 1 is a view showing in rear elevation, partly sectioned, one form of signal embodying my invention. Fig. 2 is a sectional view on the line II-II of Fig. 1.

Similar reference characters refer to similar parts in each of the views.

20 Referring to the drawing, the signal comprises a casing 2, provided with a rear door 2^a, which casing contains three light units, P, C and S, indicating when lighted, "proceed", "caution" and "stop", respectively.

25 Referring particularly to the "stop" unit S, it will be seen that this unit comprises an incandescent lamp 3, and a lens combination 4 for projecting a beam of light from this lamp toward a train approaching the

30 signal. The lamp 3, which I will term the main lamp of the unit, is so located that its filament is at the focus of the lens combination 4, so that the projection of light from this lamp is comparatively efficient. The

35 lens combination 4 includes a colored glass, usually red, which glass may be separate from the lenses or may be one of the lenses themselves, the result in either instance being that the light projected from this unit

40 toward a train approaching the signal is red. The light unit S also includes an auxiliary lamp 5, which is so located that its filament is a considerable distance behind the focus of the lens combination 4. The

45 unit is provided with a reflector 6, the function of which is to project light from the auxiliary lamp 5 to the focal center of the lens combination 4 from which point such light is, of course, projected in the same

50 manner as the light from the main lamp 3. The purpose of the auxiliary lamp 5 is to give a comparatively faint short-range indication in the event that the main lamp 3 burns out.

The "proceed" unit P and the "caution"

unit C, are the same as the stop unit S, consequently further explanation of these units is unnecessary, it being understood, of course, that the light projected from each unit is different in color. Ordinarily, the 60 light from the proceed unit P will be green, and that from the caution unit C will be yellow.

As is well understood in railway signaling practice, the control of the signal is usually such that as a train passes the signal the stop unit S becomes lighted to indicate to a following train that the block protected by the signal is occupied. It is frequently desirable, however, that the engine driver 70 should be able to determine that the stop unit S has become lighted, or that this fact should be apparent to others on the train which has passed the signal. For this reason I have provided a back light for the 75 stop unit S which I will now describe.

Located above the main lamp 3 is a frame 7 attached to the casing 2 and containing a condensing lens 8, which lens projects a beam of light from the lamp 3 upwardly 80 and slightly to one side as will be apparent from Fig. 1. Located in the path of this beam is a mirror 9 attached to a suitable frame 10 mounted in the signal casing 2, which mirror deflects the beam horizontally 85 toward the back of the signal. This beam of light passes through a glass window 11 in the rear door 2^a, which window is protected by a hood 12 to shield the window from outside light. The inner surface of the glass 90 window 11 is preferably sandblasted or ground in other suitable manner.

It will be seen from the foregoing that when the main lamp 3 of the stop unit S is lighted, an uncolored beam of light from 95 this lamp is projected from the back of the signal, so that it may be seen from a train moving away from the signal. This beam of light will indicate to persons on such a train that the train is protected by a stop 100 indication, thus showing positively that the signal is functioning in the proper manner.

It will be noted that light from the auxiliary lamp 5 is not projected through the opening 11, the reason for this being that 105 lamp 5 is an auxiliary lamp only, and is provided to avoid interruption to traffic if the main lamp 3 should burn out. When the auxiliary lamp 5 is lighted and the main lamp 3 is extinguished, the signal is not 110

functioning in its normal manner, and so it is not desirable at such time to project a beam of light through the window 11.

One feature of the specific structure shown in the present application is that any light from an outside source which may enter the rear window 11 and reach the mirror 9 will not be projected from the front of the signal through the lens combination 4 10 of the stop unit S.

Although I have herein shown and described only one form of signal embodying my invention, it is understood that various changes and modifications may be made 15 therein within the scope of the appended claims without departing from the spirit and scope of my invention.

Having thus described my invention, what I claim is:

- 20 1. A light signal comprising optical means for projecting a beam of light towards a train approaching the signal, a main lamp located substantially at the focal point of said optical means, an auxiliary lamp located 25 well out of the focal point of said optical means but in such position that light is projected therefrom by said means, and other means for projecting a beam of light from said main lamp but not from said auxiliary lamp towards a train leaving said signal.
- 20 2. A light signal comprising optical means for projecting a beam of light towards a train approaching the signal, a main lamp located substantially at the focal point of said 35 optical means, an auxiliary lamp located in the rear of said focal point, a reflector located behind said auxiliary lamp for projecting light therefrom to said focal point, and means including a mirror for projecting 40 a beam of light from said main lamp around said reflector and out at the back of the signal.
- 45 3. A light signal comprising optical means for projecting a beam of light towards a train approaching the signal, a main lamp located substantially at the focal point of said optical means, an auxiliary lamp located in the rear of said focal point, a reflector located behind said auxiliary lamp for 50 projecting light therefrom to said focal point, a condensing lens for projecting a beam of light from said main lamp at substantially right angles to the axis of said optical means, and a mirror for directing 55 said last-mentioned beam of light toward an opening in the back of the signal.
- 60 4. A light signal comprising a lamp, optical means for projecting a beam of light from said lamp out of the front of the signal, a lens for projecting an additional beam of 65 light from said lamp at substantially right

angles to the axis of said optical means, and a mirror for directing said last-mentioned beam of light toward an opening in the back of the signal, the openings in the front and back of the signal being non-registering, and the part of the back wall registering with the front opening being opaque so that light from the outside striking the back of the signal cannot be projected from the front 70 opening to cause the signal to falsely appear illuminated.

5. A railway light signal comprising a casing having two non-registering apertures in the front and back respectively, a light source located in said casing in the axial line of the front aperture, a lens mounted in said front aperture for projecting a beam of light towards a train approaching the signal, and means for projecting a second beam of light 80 from said source through said back aperture towards a train receding from said signal, the part of the back wall of said casing registering with said front aperture being opaque so that light from the outside striking the back of the casing cannot be projected from the front aperture to cause the signal to falsely appear illuminated.

6. A railway light signal comprising a casing having two non-registering apertures in the front and back respectively, a lens mounted in the front aperture, a light source located in said casing in the axial line of said lens, and means for projecting through said back aperture a beam made up of rays from said source which could not be utilized by said lens, the part of the back wall of said casing registering with said front aperture being opaque so that light from the outside striking the back of the casing cannot be 95 projected from the front aperture to cause the signal to falsely appear illuminated.

7. A railway light signal comprising a casing having two non-registering openings in the front and back respectively, a light source located in said casing in the axial line of said front aperture, a lens mounted in said front aperture for receiving a conical beam from said source and transmitting it as a beam of parallel rays towards a train approaching said signal, and means for projecting through said back aperture a beam made up of rays from said source not included in the conical beam received by said lens, the part of the back wall of said casing registering with said front aperture being opaque so that light from the outside striking the back of the casing cannot be projected from the front aperture to cause the signal to 115 falsely appear illuminated.

In testimony whereof I affix my signature.
JOHN S. HOBSON.
